(57) **CLAIM**

The ornamental design for a drinking bottle, as shown and described.

DESCRIPTION

FIG. 1 is a top view of a drinking bottle, showing my new design.

FIG. 2 is a bottom view thereof.

FIG. 3 is a front view thereof.

FIG. 4 is a right side view thereof, the left being the mirror image thereof.

FIG. 5 is a rear view thereof.

FIG. 6 is a top, front, right side perspective view thereof; and,

FIG. 7 is a bottom, front, left side perspective view thereof. The broken lines in the figures illustrate portions of the drinking bottle that form no part of the claimed design.
